METHOD OF REFINING MINERAL OILS

Ernest Terres, New York, and Erich Saegebarth, Long Island City, N. Y., and Joseph Moes, Berlin-Mariendorf, and Hans Ramser, Berlin-Steglitz, Germany, assignors, by mesne assignments, to Edeleanu Gesellschaft m. b. H., Berlin, Germany, a corporation of Germany

Application May 23, 1935, Serial No. 23,130

6 Claims. (Cl. 196—13)

Our invention relates to the refining of mineral oils by means of solvents and particularly relates to the use of organic and inorganic fluorine compounds in liquid state, which we have discovered to be particularly advantageous for different types of oil refining treatment.

We have found that liquid or liquefied fluorine compounds can be used as solvents or diluents for deasphaltizing and for dewaxing, in the manner that liquid propane is sometimes used. Also, that under certain circumstances some of these compounds can likewise be used as selective solvents for solvent fractionation of oils, and that these compounds can be used to good effect in conjunction with other solvents which are either selective or non-selective with the fluorine compounds or the oils to be treated.

The fluorine compounds can also be advantageously used in some cases as diluents for oil to be acid treated, as by dissolving the oil in a liquid or liquefied fluorine compound and treating with sulfuric acid to remove unstable constituents of the oil. Various uses of the fluorine compounds will be illustrated in subsequent examples.

The fluorine compounds which we consider as coming within the scope of this invention may be divided into three broad classes, namely:

(1) Aliphatic fluorine compounds, that is, fluorine derivatives of aliphatic hydrocarbons having either straight or branched chains, or both, including both saturated and unsaturated hydrocarbons, in which one or more or all of the hydrogen atoms are substituted by fluorine, and which may also contain other substituted halogens such as chlorine and bromine.

(2) Aromatic fluorine compounds.

(3) Inorganic fluorine compounds.

Representative organic fluorine compounds coming within class (1) are as follows:

Paraffine derivatives.—Mono-, di-, and tri-fluoromethane, and carbon tetrafluoride. Mono- to hexa-fluoroethanes. Fluorine derivatives of propane, butane and higher paraffines. (The introduction of one or more fluorine atoms into propane may increase its specific qualities for oil refining purposes, such as selectivity and suitability for deasphaltizing and for dewaxing.)

Fluorinated paraffines also containing other halogens, such as monochloromonofluoromethane, dichloromonofluoromethane, trichloromonofluoromethane, dichlorodifluoromethane, unsym.trichlorotrifluoroethane, monochlorotrifluoromethane, monochlorodifluoromethane, monobromomotrifluoromethane. Dichlorotetrafluoroethane,

pentachloromonofluoroethane, sym.tetrachlorodifluoroethane, trichlorotrifluoroethane, sym.dichlorotetrafluoroethane, unsym.dichlorotetrafluoroethane, monochloropentafluoroethane, unsym.tetrachlorodifluoroethane, unsym.tetrachlorodifluoroethane. Monofluorodibromotrichloroethane, difluorodibromodichloroethane, trifluorodibromomonochloroethane, tetrafluorodibromoethane, sym.difluorodibromodichloroethane. Also, corresponding derivatives of propane and butane.

Representatives of this class for which subsequent examples are given are dichloromonofluoromethane, trichloromonofluoromethane, dichlorodifluoromethane and monobromodifluoromethane.

Unsaturated aliphatic fluorine derivatives.—Dichlorodifluoroethylene, monochlorotrifluoroethylene, trichloromonofluoroethylene, tetrafluoroethylene, sym.dichlorodifluoroethylene and isomers thereof.

Representative aromatic fluorine compounds coming within class (2) are as follows:

Monofluorobenzol, difluorobenzol, fluorophenols, monofluoronaphthalene and other fluorine and fluorine-halogen derivatives of benzol and its homologues.

Representative inorganic fluorine compounds coming within class (3) are as follows:

Sulfur-containing compounds and other inorganic compounds.—Sulfuricoxyfluoride, sulfuroxyfluoride, sulfurylfluoride, thionylfluoride, fluorosulfinic acid, fluorosulfonic acid, disulfur-difluoride, sulfur-disfluoride, sulfur-tetrafluoride, and sulfur-hexafluoride. Also corresponding compounds containing selenium or tellurium which do not react with oil.

Other inorganic compounds.—Fluorine compounds of nitrogen, antimony, arsenic and tin, such as nitrogentrifluoride, antimony-pentafluoride, arsenic-pentafluoride and arsenic-trifluoride. Also, compounds of boron such as the addition compound of hydrofluoric acid and metaboric acid having the formula: $HBO_2 \cdot H_2F_2$; and compounds of silicon which do not react with oil.

The representatives of class (3) for which subsequent examples are given to indicate their action are sulfuric-oxyfluoride and sulfur-hexafluoride.

By the expression fluorine-halogen compounds or derivatives as hereinafter used is meant a compound which contains one or more of the other halogens, besides fluorine.

The foregoing fluorine compounds find appli-

cation, according to our invention, in the following types of refining processes illustrated in the accompanying diagrams:

(A) Deasphalting.

5 Some of the fluorine and fluorine-halogen derivatives are suitable for deasphalting insofar as they dissolve hydrocarbon oils entirely at proper temperatures, whereas asphaltenes are left undissolved. By separating the two layers 10 and recovering the solvent from them, a residual oil can be separated into asphaltines and deasphalting oil.

(B) Dewaxing.

15 Some of the fluorine derivatives are suitable as dewaxing agents either alone or in combination with solvents which are soluble in the oil to be dewaxed as well as in the fluorine solvent, for example: benzol, toluol, methylchloride, ethylchloride, carbon bisulphide, ether, esters and others.

20 (C) Selective solvent extraction.

Some of the mentioned fluorine derivatives may be used for solvent extraction, in which case five different methods of applications may be employed, namely:

25 (a) One of the mentioned fluorine or fluorine-halogen derivatives may be used alone or in mixtures with others.

(b) The fluorine or fluorine-halogen derivatives mentioned under (a) may be used in mixture with one or more solvents of the class which is miscible in any proportion with the hydrocarbon oil to be treated and with the fluorine or fluorine-halogen selective solvent. Examples of such solvents are given under the heading (B) dewaxing.

30 (c) The fluorine or fluorine-halogen derivatives mentioned under (a) may be used in mixture with one or more solvents of the class which is miscible in any proportion in the fluorine or fluorine-halogen selective solvent but which is not miscible or only to a small degree in the hydrocarbon oil to be treated.

35 Representatives of the latter group of auxiliary solvents are, for example, water or alcohol. These auxiliary solvents serve to decrease the solvent power of the fluorine or fluorine-halogen selective solvent, whereas the group of auxiliary solvents mentioned under (b) tend to increase the solvent power of the selective solvent.

40 (d) The fluorine and fluorine-halogen compounds mentioned under (a) may also be used for solvent extraction in presence of another selective solvent with which they form two layers under proper conditions. Examples of combinations of solvents having this characteristic are given later.

45 We have disclosed under (A) above that some fluorine or fluorine-halogen solvents are capable of dissolving hydrocarbons entirely with the exception of asphaltenes. We have found that such fluorine or fluorine-halogen solvents may be used for extraction purposes in combination with a selective solvent which preferably dissolves the undesirable fractions of hydrocarbon oils but which at the same time forms two layers with the fluorine or fluorine-halogen solvent.

50 (e) For the same purposes as mentioned under (d) we may also employ a solvent for refining purposes which is only selective with respect to the fluorine and fluorine-halogen solvents but not with respect to the hydrocarbon oils, such as propane.

55 In the accompanying drawings, which show with the aid of explanatory legends several modes

of carrying out the invention for purposes of illustration,

Fig. 1 is a flow diagram illustrating the use of our fluorinated solvents in the successive treatments of an asphaltic waxy oil stock for asphalt removal, wax removal and separation of the oil into a raffinate fraction and an extract fraction by means of a selective solvent.

60 It will be understood, if the oil stock to be treated in accordance with the method illustrated by the flow diagram Fig. 1 does not contain asphalt but only wax, that the deasphalting step may be by-passed and the solution of oil stock in the fluorine containing solvent may be directly introduced into the dewaxing apparatus, 15 which is indicated in the diagram by the chilling and filtering steps. Likewise, it will be understood, if the oil stock to be treated contains asphalt but no wax, that the dewaxing step may be by-passed and the deasphalting oil-solvent solution may be directly subjected to extraction with the selective solvent.

65 In the extraction step, the deasphalting and dewaxed solution of oil in fluorine containing solvent may be extracted with a selective solvent 25 alone; or it may be extracted with a mixture of the selective solvent and the fluorine containing solvent, in which latter case part of the fluorine containing solvent flows directly from the supply to the extraction stage as shown in Fig. 1, 30 and joins the selective solvent, prior to entering the "mixing and settling" step.

70 In the flow diagram Fig. 2, a method is illustrated in which an asphaltating waxy oil stock is freed from asphalt and wax by means of a fluorinated solvent in the same manner as shown in Fig. 1; and thereafter, the oil-solvent solution is heated until separation into two liquid phases takes place, said phases consisting of a dissolved phase, or raffinate phase, and an undissolved 40 phase, or extract phase. By recovering the solvent from each of said phases the raffinate and the extract are obtained, respectively.

75 It has been found that dichloromonofluoromethane and trichloromonofluoromethane dissolve mineral oil entirely at temperatures in the neighborhood of or above the pour point of oils which contain wax; also asphaltenes are dissolved entirely. Upon reducing the temperature of the solution containing the waxy lubricating oil distillate dissolved in trichloromonofluoromethane, the wax crystallized out but a separation of two liquid phases is not obtained at low temperatures.

80 In the following an example is given for the dewaxing of a Midcontinent overhead cylinder stock by means of trichloromonofluoromethane.

Example 1

85 One volume of a Midcontinent overhead cylinder stock having 10% wax, an A. P. I. gravity of 22.1, a S. U. viscosity of 154 at 210° F. and a pour point of 110° F. was dissolved in 2½ volumes of trichloromonofluoromethane, cooled to -50° F. and passed through a filter at this temperature. After removal of the solvent from the filtrate an oil of 26° A. P. I. 182 S. U. viscosity at 210° F. and of a wax content of zero, was obtained. The slack wax showed a melting point of 130° F.

90 Dichloromonofluoromethane showed the same behavior as outlined for trichloromonofluoromethane.

95 In agitating dichloromonofluoromethane with certain selective solvents, including chlorophenol, aniline, furfural, nitromethane, furfurylalcohol and others, it has been found that these selective

solvents are entirely miscible in dichloromonofluoromethane and a phase separation does not occur even at temperatures as low as -50° F.

Contrary to this experience trichloromonofluoromethane gives a phase separation with aniline, nitromethane, furfural, furfurylalcohol and others at low temperature, being only partially soluble therein, whereas it is entirely miscible with chlorophenol, quinoline, benzylalcohol, bromonaphthalene and others.

Dichloromonofluoromethane and trichloromonofluoromethane can therefore be used as auxiliary solvent in combination with selective solvents with which they are entirely miscible. The presence of dichloromonofluoromethane or trichloromonofluoromethane increases the solvent power of the selective solvent and the treating result can be controlled by the quantity of dichloromonofluoromethane or trichloromonofluoromethane used.

Trichloromonofluoromethane may also be used in combination with aniline, nitromethane, furfural or furfurylalcohol, in which case the largest amount of trichloromonofluoromethane will serve as diluent and solvent for the raffinate phase, whereas the extract phase will contain the selective solvent and the oil extract both saturated with the auxiliary solvent trichloromonofluoromethane.

The action of dichlorodifluoromethane is quite different from the behavior of trichloromonofluoromethane or dichloromonofluoromethane in so far as it has no solubility for asphaltenes and its insolubility in selective solvents is more pronounced.

Residual oils may be freed from asphaltenes by extraction by means of dichlorodifluoromethane. The non-asphaltenic hydrocarbons are dissolved entirely, whereas the asphaltenes form a separate layer and may be segregated in the normal way. This is shown in more detail in the following example.

Example 2

A Midcontinent residual oil of 20° A.P.I. gravity, 145 S. U. viscosity at 210° F. and 997 at 130° F., and 5.6 carbon residue, was agitated with 4 volumes dichlorodifluoromethane at 130° F. Two layers were formed. The upper layer consisted of the asphaltenes and contained some dichlorodifluoromethane in solution, while the lower layer comprised the bulk of dichlorodifluoromethane and contained the hydrocarbon oil in dissolved form. The phases were separated and freed from the solvent. Yields and specifications of the deasphaltized oil were as follows:

Yield	percent	87
A.P.I.	degrees	21.9
Viscosity at 130° F.		664
Viscosity at 210° F.		109
Carbon residue		3.8

The yield of asphalt amounted to 13% by volume. Dichlorodifluoromethane is also suitable for de-waxing purposes. The deasphaltizing and dewaxing processes may also be combined. In such case a residual oil, for example, may be treated with the solvent in the neighborhood of 130° F. and the asphalt-free solution then cooled to the dewaxing temperature and filtered. If desired, as may be the case with oils containing only small quantities of asphaltenes, the separation of oil and wax may even be carried out in one operation by dissolving the stock in the solvent and cooling it to the dewaxing temperature and filtering it, in

which case the asphaltenes will be separated with the wax.

In treating mineral oils with dichlorodifluoromethane it is necessary to consider that the temperature range of entire miscibility is limited because this solvent shows a negative temperature coefficient in regard to the solubility of mineral oils. Upon heating the solution of asphalt-free oil in the solvent, a point can be reached at which separation into two liquid phases occurs. One of the two phases contains the bulk amount of solvent, having a certain amount of oil in solution. This amount of oil is the smaller, the higher the temperature. The other phase contains the undissolved and separated oil which is, of course, saturated with the solvent. Such phase separation will occur with a heavy cylinder stock at about 212° F. The specific gravity of dichlorodifluoromethane, which is 1.5 at -36° F., decreases to 0.83 at 225° F. The position of the two layers may therefore be reversed, depending upon the temperature of the operation and the gravity of the oil.

Example 3

A 650 steam refined stock of 24.3° A.P.I. gravity, 231 Saybolt S. U. viscosity at 210° F., and 3.4 carbon residue, was treated with 4 volumes of dichlorodifluoromethane at 212° F. Two layers were formed. The phases were separated and freed from the solvent. The specifications of the two oil fractions obtained are shown in the following table:

	Undissolved oil	Dissolved oil	35
Yield, volume	percent	89.4	10.6
A. P. I.	degrees	23.6	27.3
Viscosity at 130° F.		1790	-----
Viscosity at 210° F.		255	-----
Carbon residue		4.1	1.2

Dichlorodifluoromethane is not entirely miscible with certain selective solvents, such as quinoline, aniline, dichloroethylether, cresol, phenol, chlorophenol and others. It is therefore possible to use it in combination with the above mentioned solvents in the same manner that propane is used. This procedure is especially advantageous for the treatment of residual oils and is likewise applicable to distillates, as shown by the following examples.

Example 4

One volume of a Midcontinent residual cylinder stock, with properties as shown in the table of the next example, was agitated with four volumes of dichlorodifluoromethane and one volume of phenol at 104° F. The layers were allowed to settle afterwards and were separated.

The raffinate layer was treated again with one volume of phenol at the same temperature of 104° F. The layers were again separated and the solvent was removed from the final raffinate and from the combined extract phases. The properties of the raffinate are shown in the table of the next example.

Example 5

One volume of the same Midcontinent stock referred to in the preceding example was agitated with four volumes of dichlorodifluoromethane and one volume of parachlorophenol at 140° F. Upon separation of the layers, the raffinate phase was treated again with one volume parachlorophenol at 140° F. Upon removal of the

solvents from the final raffinate and the combined extract phases, the refined oil was obtained and the properties are shown in the following table:

5		Original oil	Raffinate, Example 4	Raffinate, Example 5
10	Yield, volume percent	100	66	51
	A. P. I. degrees	20	24.5	27.5
10	Viscosity at 130° F.	997	524	320
	Viscosity at 210° F.	145	98	77
10	Carbon residue	5.6	-----	0.67

Example 6

15 A dewaxed Midcontinent oil distillate was treated with 3 volumes of dichlorodifluoromethane and 1 volume of aniline at 104° F. The layers were allowed to separate and were then freed of these solvents. The refined oil was 20 contacted with 10% diatomaceous earth or other filter aid at 450° F. The properties of the finished raffinate are shown in the table given in the next example.

Example 7

25 The same dewaxed Midcontinent lubricating oil distillate was extracted with 2 volumes of dichlorodifluoromethane and two volumes of parachlorophenol at 113° F. The phases were 30 separated again and the solvents were recovered by distillation. The specifications of the refined oil are shown in the following table:

35		Untreated stock	Raffinate, Example 6	Raffinate, Example 7
	Yield volume percent	100	90	70
	A. P. I. degrees	23.2	24.9	27.5
	Viscosity at 100° F.	1287	1051	735
40	Viscosity at 210° F.	91	84.5	74.8
	V. I.	75	84	94
40	Carbon residue	1.9	1.1	0.42

45 The following examples indicate the selective solvent action of sulfuricoxyfluoride and sulphur hexafluoride for refining naphthas, kerosenes and lubricating oils.

Example 8

One volume of straight-run naphtha was agitated with one volume sulfuricoxyfluoride and cooled to -50° F., at which temperature a separation into two phases occurred.

Example 9

55 A lubricating oil distillate of 75 viscosity at 210° F. and 28° A. P. I. gravity was agitated with an equal volume of sulfuricoxyfluoride at room temperature. A separation into two phases occurred.

Example 10

60 A Midcontinent residual oil upon agitation with an equal volume of sulfuricoxyfluoride at 87° F. showed a separation into two layers.

Example 11

65 Equal volumes of chlorphenol and sulfuricoxyfluoride were brought in contact at room temperature and cooled to 32° F. Separation took place at this temperature, whereas above 32° F. chlorophenol was entirely dissolved in sulfuricoxyfluoride.

70 Our study of the four fluorine compounds, namely:

Dichloromonofluoromethane
Trichloromonofluoromethane
Dichlorodifluoromethane (known as Freon)
Sulfuricoxyfluoride

shows a different action of the respective fluorine compounds depending upon the other atoms present in the molecule. Whereas methane, ethane, propane, and other low boiling paraffines, are selective against mineral oils at proper temperatures and against asphaltenes, this behavior is changed by the introduction of chlorine or bromine into the molecule. As known, methylchloride, carbontetrachloride or tribromomethane dissolve mineral oils and asphaltenes entirely. However, the introduction of fluorine into a chlorinated paraffine seems to restore the selectivity, as shown by dichlorodifluoromethane, and others including monochlorotrifluoroethane, dichlorotrifluoroethane, dichlorodifluoroethane, dichlorotetrafluoroethane, monochlorotrifluoromethane, monobromodifluoroethane, and monochlorodifluoroethane.

Monofluorine derivatives of chlorinated paraffines, such as dichloromonofluoromethane and trichloromonofluoromethane, do not possess the selectivity of dichlorodifluoromethane. It appears, therefore, that more than one fluorine atom has to be present in these derivatives in order to cause the solvent to be selective.

The introduction of one or more fluorine atoms into propane or other solvent will change its specific qualities for oil refining purposes, such as selectivity, suitability for deasphalting and for dewaxing (by decreasing the solubility in the oil) so that it becomes more than a diluent and can be used as a selective solvent. Examples of such fluorinated solvents are the following: trifluoropropane, difluoropropane, monofluoroethane, difluoroethane, monofluoromethane, difluoromethane, trifluoromethane, and carbontetrafluoride.

The use of dichlorodifluoromethane, in accordance with our invention, is described and claimed specifically in our copending application filed of even date herewith.

In the claims the term "liquefied" means that the substance referred to is used in a liquid state, whether normally liquid or not, and the expression "predominantly fluorine containing" means a halogenated derivative of an organic substance containing one or more fluorine atoms in excess of such other halogen atoms as may be contained therein.

We claim the following as our invention:

1. A method of refining a waxy mineral oil stock comprising dissolving the oil in a liquefied organic fluorine compound in which the oil is soluble and at low temperatures the wax is insoluble, chilling the mixture to a low temperature at which the wax separates out, removing the separated wax, and heating the solution in a separate step to a higher temperature to bring about phase separation, and separating the phases.

2. A method of refining a waxy mineral oil comprising dissolving the oil in a fluorine derivative of an aromatic hydrocarbon containing no oxygen, chilling the solution to a temperature at which the wax separates out, removing the wax, and extracting at an elevated temperature with a selective solvent.

3. A method of refining a mineral oil containing asphalt comprising dissolving the oil in a fluorinated derivative of an aromatic hydrocarbon containing no oxygen, separating out the undissolved asphalt, chilling the solution to precipitate out wax, and removing the wax.

4. The process of refining a mineral oil comprising dissolving the soluble constituents of the

oil in a liquefied predominantly fluorine containing halogenated organic compound, separating the undissolved constituents, treating the solution with a mixture of said compound and a solvent selective with respect thereto to extract undesirable constituents of the oil, and separating the phases thereby formed.

5. The process of refining a mineral oil comprising dissolving the soluble constituents of the oil in a liquefied predominantly fluorine containing halogenated organic compound, separating the undissolved constituents, treating the solution with a mixture of said compound and a solvent miscible therewith and selective with respect to the oil to extract undesirable constitu-

ents of the oil, and separating the phases thereby formed.

6. The process of refining a mineral oil comprising dissolving the soluble constituents of the oil in a liquefied predominantly fluorine containing halogenated unsaturated hydrocarbon compound, separating the undissolved constituents, treating the solution with a mixture of said compound and a solvent selective with respect thereto to extract undesirable constituents of the oil, and separating the phases thereby formed.
